PIEZOELECTRIC CRYSTAL

Andrew E. Swickard, Chicago, Ill., assignor to
 Western Electric Company, Incorporated, New
 York, N. Y., a corporation of New York

Application April 9, 1943, Serial No. 482,361

7 Claims. (Cl. 171—327)

This invention relates to piezoelectric crystals, and more particularly to piezoelectric crystals having a low frequency mode of vibration.

An object of the present invention is to provide an efficient and effective low frequency piezoelectric crystal.

In accordance with one embodiment of this invention, a piezoelectric crystal of substantially parallelopiped shape may be provided having lead wires attached to either side at a point 10 approximately in the middle of the crystal to create an artificial nodal point and to cause the crystal to be resonant at a low frequency.

Other objects and advantages of the present invention will be apparent from the following detailed description taken in conjunction with the following drawing, wherein:

Fig. 1 shows a perspective view of a piezoelectric crystal mounted in accordance with the present invention, and

Fig. 2 shows diagrammatically the low frequency mode of vibration of a piezoelectric crystal supported in accordance with the present invention.

When a low frequency piezoelectric crystal is required, as in certain types of carrier circuits in telephone apparatus, it has sometimes been the practice to employ a quartz crystal of rather large dimensions and having a flexure mode of vibration. The frequency for a given size of flexure vibration type crystal, when vibrating in free flexure, is indicated by the following formula:

$$f = \frac{m^2}{2\pi\sqrt{12}} \frac{W}{L^2} \sqrt{\frac{Y_o}{P}}$$

wherein "f" equals the frequency in cycles per second; "W" equals thickness; "L" equals length or width; "m" equals $(n+\frac{1}{2})$; "n" equals 1, 2, 3, 4, etc. (any integer); "Y_o" equals Young's modulus; and "P" equals density.

When a CT cut crystal is vibrated in a free flexure vibration, the natural nodal points occur at the points 4 in the crystal. However, when it is attempted to mount the crystal at these points, it will be found that the crystal has a very low activity when driven at a low frequency or it may have no activity at all. By mounting such a crystal at a point between these natural nodal points, it appears that a new, or what may be called an artificial nodal point is created, and when the crystal is then driven at a low frequency, it will be found to have a high response or high activity.

In accordance with the present invention, a

pair of lead wires 5 may be attached to the center of a CT cut crystal 6, that is, a crystal having one edge parallel to its electrical axis and the other 38° from the optical axis, of substantially square or parallelopiped shape. The other ends of the lead wires are soldered to supporting springs 7 positioned on either side of the crystal 6 and fixed to oppositely disposed terminals 8, mounted in a supporting block 9 and extending therethrough. The following formula gives the approximate frequency for this type of crystal when mounted in accordance with the present invention and driven at its lowest frequency:

$$f = K \frac{m^2}{2\pi\sqrt{12}} \frac{W}{L^2} \sqrt{\frac{Y_o}{P}}$$

wherein "K" equals approximately one-half (1/2).

It appears that this low frequency mode of vibration is of the flexure type and that the unusually low frequency of such crystals is due in part at least to the single point of suspension of the crystal, as illustrated in Fig. 2. Where a crystal is supported at more than one point, it will be apparent that considerably greater stiffness results than where a single support is employed. The cut of the crystal is also important and the CT cut gives desirable results.

In practice it has been found that if a CT cut crystal approximately .386" square and .019" thick is wire mounted with the lead wires attached to the center of either side of the crystal, a low frequency of vibration on the order of 21 kc. per second is obtained. The frequency of this vibration can be varied by changing the plate thickness and width as shown in the second formula above.

A crystal of this type, mounted as described herein, is substantially more active and, consequently, more efficient than the standard low frequency X cut crystal of the same frequency, that is, a crystal having one edge perpendicular to the electrical axis and the other parallel to the optical axis. In addition, it may be, as indicated in the formula given above, approximately one-half (1/2) the size of an X cut crystal of the same frequency. This reduction in size is a considerable advantage where one or more such crystals are to be used since it reduces the space required in the apparatus for housing it. Because of this reduction in size, the cost of such crystals is substantially reduced as compared with other crystals such as the X cut of similar frequency range.

What is claimed is:

1. A CT cut piezoelectric crystal for low fre-

quency vibration of such area relative to its thickness as to have free vibration nodal points spaced along one dimension, and a support for said crystal substantially midway between said nodal points whereby an artificial nodal point is formed causing the crystal to vibrate at a low frequency.

2. A CT cut piezoelectric crystal of such area relative to its thickness as to have a low frequency mode of vibration supported at a single point on either side and vibrating in flexure.

3. A piezoelectric crystal having a single support fixed to either side thereof, and having a frequency of vibration indicated by the formula

$$f = K \frac{m^2}{2\pi\sqrt{12}} \frac{W}{L^3} \sqrt{\frac{Y_o}{P}} \quad 16$$

4. A CT cut piezoelectric crystal supported at an artificial nodal point and having such area relative to its thickness that when driven at a

low frequency it vibrates in a flexure mode of vibration.

5. A CT cut piezoelectric crystal supported at an artificial nodal point and having such area relative to its thickness that when driven at a frequency on the order of 21 kc. it vibrates in a flexure mode of vibration.

6. A CT cut piezoelectric crystal of such area relative to its thickness as to have a low frequency mode of vibration supported at a single point on either side and vibrating in flexure.

7. A CT cut piezoelectric crystal having a single support fixed to either side thereof and having a frequency of vibration indicated by the formula

$$f = K \frac{m^2}{2\pi\sqrt{12}} \frac{W}{L^3} \sqrt{\frac{Y_o}{P}}$$
